US00D896794S

(12) **United States Design Patent** (10) Patent No.: **US D896,794 S**
(45) Date of Patent: **** Sep. 22, 2020**

(54) **ANTENNA**

- (71) Applicant: **SHENZHEN ANTOP TECHNOLOGY LIMITED**, Shenzhen (CN)
- (72) Inventor: **Ruidian Yang**, Shenzhen (CN)
- (73) Assignee: **SHENZHEN ANTOP TECHNOLOGY LIMITED**, Shenzhen (CN)

(**) Term: **15 Years**

(21) Appl. No.: **29/703,293**

(22) Filed: **Aug. 26, 2019**

Related U.S. Application Data

(57) **CLAIM**

The ornamental design for an antenna, as shown and described.

DESCRIPTION

FIG. 1 is a front elevational view of an antenna showing my new design;

FIG. 2 is a rear elevational view thereof;

FIG. 3 is a top plan view thereof;

FIG. 4 is a right side view thereof, the left side view being a mirror image thereof;

FIG. 5 is a front, left perspective view thereof;

FIG. 6 is a front, bottom perspective view thereof; and,

FIG. 7 is a front, top perspective view thereof.

1 Claim, 7 Drawing Sheets
